AUTOMATIC SHUTTLE CHANGING MEANS
FOR WEAVING LOOMS

Emile Achille Butin, Lyon, France

Application December 11, 1946, Serial No. 715,419
In France December 17, 1945

8 Claims. (Cl. 139—239)

1

My invention has for its object an improved automatic shuttle changing device for weaving looms, which eliminates the drawbacks of the arrangements existing to this day. Said prior arrangements generally fall into two categories, to wit:

(a) Those wherein the change of shuttle is operated during the operation of the loom and which by reason of the speed at which this change is made, produce frequent accidents such as the breaking of the shuttle or of different parts, set in motion with too great a roughness.

(b) Those wherein the loom is stopped during the time required for the changing of the shuttle. This results in a loss of time and consequently in a reduction of production, requiring an intricate and bulky braking and starting mechanism.

The change of shuttle according to my invention relies on the fact that the box located on the change side serving to receive and start the shuttle plays a useful part only during one-half revolution of the crank-shaft out of two complete revolutions.

A primary object of my invention consists in making use of the three half revolutions during which the shuttle-box does not have any useful function for disengaging it with reference to the batten and holding it in register with a casing containing substitute shuttles which provides thus all the time required for the downward movement inside said box of the next shuttle without any shock or rough treatment. Once this change has been executed, the box resumes its normal cycle of operation as it follows the batten with which it moves in unison up to the next change of shuttle.

This removes the drawbacks of the two systems of shuttle-changing generally used nowadays in weaving looms, and as stated above.

As a matter of fact, the time available for producing a change of shuttle is sufficiently long for it to be possible to execute it smoothly without however the loom itself standing still. At the same time this removes the intricate and bulky means used heretofore for braking and starting again the loom.

On the other hand, the inertia of the moving parts being practically zero, the drive of the loom may be ensured through the usual means of an ordinary loom, i. e. for instance through a belt and a set of loose and fast pulleys.

Moreover the loading of the shuttle-box being executed beyond the extreme rear position of the batten, the front part of the loom remains perfectly free.

2

According to a further object of my invention, a frame is pivotally secured to an extension of the rocking-shaft of the batten and forms, at its upper part, the box inside which the shuttle is to be engaged, the front wall of this box being pivotally secured to said frame and adapted to move away therefrom at the moment of the change of shuttle so as to receive the next shuttle through the action of levers which engage slopes and the pivoting of which is produced by a cam.

According to a further object of my invention, the engagement and disengagement between the batten and the frame are obtained through the said levers which control at the same time the opening of the box as disclosed.

According to a still further object of my invention, the above frame which rocks round an axis lying in alignment with the axis of reciprocation of the batten and which follows the same during its reciprocation, while allowing its disengagement when it is desired that it should remain stationary in its rear position while the batten executes its complete cycle of operation, includes in addition to its opening box the whole mechanism comprising the weft-feeler which controls said mechanism.

According to a particular feature of this form of execution, all the parts of the frame producing the various movements required, to wit: the feeling of the cop, the disconnection of the frame with reference to the batten, the feeding of the next shuttle, the release of the shuttle when it is to be started, and also the reverse movements which return said parts into their original position, are ensured by a set of cams all keyed to the same shaft rotating at half the speed of the crank-shaft of the loom; the operation of the said cams in the case of the cams controlling the various movements which are to be made only at the moment of the change of shuttle, is provided by a translational movement of said shaft which places said cams in front of the levers to be controlled thereby.

According to a still further feature of my invention, this translational movement of the shaft is produced by the release through the feeler of a projection which enters the path of the boss of one of the said cams, which forces the latter to recede while producing the desired translational movement.

This manner of applying my invention will be better understood by referring to the accompanying diagrammatic drawings corresponding with the case of a simple stroke loom. It is of course to be understood that it is applicable as well to a

multiple stroke loom, and only the holder or casing for the shuttles which does not form part moreover of my invention, should be suitably designed in this case. In accompanying drawings:

Fig. 1 is a perspective view seen from the front and side of the whole weaving loom equipped according to my invention.

Fig. 2 is a perspective view through the rear of the oscillating frame and various members in their non-released position, the batten and extension thereof being however removed from said perspective view and only the hooks provided on said extension being illustrated for greater clarity of the illustration.

Fig. 3 is a view similar to Fig. 1 illustrating only the shuttle locking means.

Fig. 4 shows the sensing member in elevational side view at the moment of the sensing of a shuttle the cap of which is not yet exhausted.

Figs. 5 to 10 are diagrams showing in elevational side view the succession of movements at the moment of a change of shuttle.

Figs. 11 to 13 are further diagrams illustrating in plan view the relative location of the principal members in three of their positions.

Fig. 14 is a plan view of the open box with its pivoting independent cover.

Fig. 15 is a side elevational view of the same box as seen cross-sectionally through line 15—15 of Fig. 14.

As shown in the embodiment illustrated, the frame 1 is provided with two supports 1a pivotally secured to a shaft 2 arranged in alignment with the shaft carrying the batten A and forming an extension thereof.

The frame 1 includes a wall 1b and a shoe or step 1c (Fig. 2) defining with another wall 6 a box or compartment B opening upwardly and expansible laterally as this wall 6 forms part of an independent frame 7 pivotally secured at 8 to the arms 1a of the frame 1.

This frame 7 carries a shoe or step 10 located at the same height as the shoe 1c of the box B. This frame 7 also has two lugs 7a extending forwardly and provided each with a sloping cam opening 9.

The batten A of the weaving loom stops at A1 (Figs. 11-13), and the missing portion corresponds to the location of the above mentioned box B that shows in its bottom or shoe 1c a longitudinal slot 1d for the picker stick C.

To the end of the batten A, thus shortened, is fitted a bent iron fitting 3a and a box 3b without any bottom or cover; under this iron fitting are secured to either side of the above mentioned box 3b two transversal plates the front of which is outlined as shown at 3 so as to form a slope ending with a hook 5; the spacing between said two plates 3—5 is such that they fit between the lugs 7a of the frame 7. This box 3b is moreover positioned vertically in a manner such that it may move over said lugs 7a and fit to a slight extent underneath the shoe or step 10 as it passes between the legs of said frame 7 as allowed through the bent shape assumed by the iron fitting 3a.

The wall 1b of the box B is provided with openings 1f and 1g (Figs. 2 and 3). The latter openings 1g serve for the passage of the bosses 13 carried by a plate 13a pivotally secured at 13b to the rear surface of a plate 1b along a line perpendicular to the axis of rotation 2.

The plate 13a is provided with notches registering with the openings 1f in the wall 1b.

The frame 1 carries a shaft 16 that is driven into rotation in the direction of the arrow y at half the speed of the crank-shaft of the loom controlling the batten A. Its rotation is produced by a chain 11 controlling a sliding pinion 17 and as it rotates, said shaft may be shifted axially.

To said shaft 16 are keyed in suitable locations (Fig. 2):

A cam 18 acting on a lever 21.

A cam 19 acting on a lever 20.

A cam 22 adapted to raise an arm 23.

A cam 24 providing for a horizontal translational movement of the shaft 16 in the direction of the arrow x.

15 A locking disc 25 provided with a notch 25a and rotating adjacent a stud 26 rigidly secured to the frame 1.

A cam 27 controlling two levers 4 rigid with one another and keyed to the spindle 33 connecting them together.

A cam 28 cooperating with the lever 29.

A stop 30 serving as a bearing for a spring 31 urging the shaft 16 in a direction opposed to that of the arrow x.

The spindle 33 carries the following members adapted to rock without being capable of moving longitudinally on it:

The lever 21

The arm 23

And the lever 29.

The levers 4 keyed to the spindle 33 end with projections 4a engaging the cam openings 9 provided in the lugs 7a.

For actuating the shuttle unit through a slot 1f in the wall 1b and through a slot of the plate 13a I use for engaging the inside of the box B a rubber roller 47 carried by a bent rod 48 adapted to rock in the bearing 48a carried by the frame 1 (Fig. 3).

To the rod 48 is keyed a stop 50 that engages another stop 51 carried by the lever 21 adapted to freely rock round the spindle 33. The lever 21 carries a transversal tail end 52 adapted to be raised by the cam 18 keyed to the shaft 16. This cam acts on the tail end of the lever whatever may be the position of the shaft 16 which as disclosed hereinabove is capable of being shifted axially. A light spring 53 urges the roller 47 inside the casing or box B. A stronger spring 54 urges the lever 21 against the plate 13a carrying the bosses 13. A port 55 in the boss 13 and plate 13a provides a passage for the needle 35 of the sensing member (Fig. 4).

The frame 1 also includes a sensing device arranged as follows (Fig. 4):

A body 56 secured to the frame 1 carries two axles 57 and 58 over which may rock respectively a sensing arm 29 and an engaging lever 38. At the upper end of the body 56 is provided a bracket 59 inside which the needle 35 is adapted to move horizontally, said needle carrying at its end an adjustable stop 36, said stop being urged in the direction of the arrow z by a light spring 60 surrounding it partly. A sliding rod 37 is rigid with the upper axle 38a of the rocking lever 38. Said rod bears slidingly at 37a against the body 56 while its end opposed to the sliding end 37a is provided with a notch 61 inside which may be engaged the above mentioned stop 36. The rod 37 is urged forwardly by a spring 62 connecting the lever 38 with the body 56. The arm 23 rocking round the spindle 33 of the frame 1 carries at its upper end a projection 23a held back by the

lever 38 pivotally secured to the body 56 as disclosed. The lower end of said rocking arm 23 carries a roller 23b adapted to cooperate with the cam 24.

The sensing needle 35 may engage the box B inside which it enters through the opening 35 provided in the boss 13 and its plate 13a.

The spare shuttles 42 are held in a shuttle holder 39 secured permanently and rigidly to the frame of the loom D (Fig. 1) above the frame 1 and in a position such that said holder may lie in vertical alignment with the box B of said frame when the latter is in its rear position. The transfer into said box of a full shuttle 40 is provided by the cradles 39a (Figs. 5 to 10), the release and control of which are ensured in any known manner, said arrangement not forming part of my invention. This release is obtained through a link-work 29a connected with the lever 29 cooperating with the cam 28 keyed to the shaft 16 (Fig. 2).

To the wall 6 of the frame 7, is moreover suspended through the bracket 70 an independent cover 44 (Figs. 14 and 15) pivotally secured to the rod 71 carried by said bracket 70. The outline of said cover is that of a reversed angle bar and it is submitted to the action of a spring 72 while its nose 73 bears the end of a lever 74 pivotally secured at 75 to a projection 76 on the wall 6. This projection 76 is rigid with a stop 77 adapted to arrest the empty shuttle that is to be removed.

The operation of the arrangement is as follows:

The loom D operating normally with a shuttle 41 of which the cop carries enough weft thread, the frame 7 closes against the frame 1 through operation of the projections 4a carried by the levers 4 and located at the upper end of the cam slopes 9 as shown in Figs. 5 and 13. The system of frames 1 and 7 is then rigid with the batten A and follows its reciprocating movements from front to rear and from rear to front. As a matter of fact, the projections 4a also engage the outer end 3 of the plates rigid with the bent fitting 3a arranged endwise of the batten A. The box B is located as stated in alignment with the batten A, its bottom or shoe 1c being flush with the corresponding surface of the batten. The operative shuttle 41 enters the box B and is urged out of it as in the usual looms by the picker stick C.

The shaft 16 urged by its spring 31 occupies the position illustrated in the drawing in Fig. 2 and the cams 24, 27 and 28 move without acting on their levers respectively levers 23, 4 and 29. Only the levers 21 and 20 are submitted to the action of their cams 18 and 19 by reason of the length given to their terminal crank pins 52 and 64 and said levers 21 and 20 act respectively on the shuttle unit and on the sensing system at the moment at which the shuttle lies in the casing B as disclosed hereinafter.

The roller 47 normally engages the box B under the action of its spring 53. The stop 50 engaging the stop 51 on the lever 21 prevents the latter from bearing against the boss 13 and prevents the spring 54 from acting efficiently (Fig. 3).

When the shuttle enters the box, it urges outwardly the rubber roller 47 so that the rod 48 rocks slightly and the stop 50 rigid therewith is shifted off the stop 51. The lever 21 urged by the spring 54 bears then against the free end of the plate 13a the bosses 13 of which are urged with some strength against the shuttle and hold it fast.

At this moment, the crank pin 64 at the end of the lever arm 20 engages the low portion of the cam 19 and allows the needle of the sensing sys-

tem 35 urged forwards by its spring 60 to engage the opening 55 and the corresponding opening provided for this purpose in the shuttle (Fig. 4).

The needle bears thus slightly on the thread contained in the cop. The thickness of the layer of thread remaining on the tube of the cop does not allow the needle to engage to a sufficient depth for the stop 36 to come into engagement with the notch 61 of the rod 37. The arm 20 is then shifted forward under the action of the cam 19 which as it rotates causes the crank pin 64 of the arm 20 to rise on to the higher portion of the cam. The stop 36 is then urged backwards with the needle 35 that completely disengages the shuttle. The stop 36 slides over the rod 37 without driving it and no release of lever 23 is produced. The rotation of the shaft 16 has so driven the cam 18 that, at the moment where the needle of the sensing device has completely disengaged the shuttle, cam 18 raises the lower crank pin 52 on the lever 21 (Fig. 3). The upper part of said lever no longer bears against the plate 13a and as it moves away from it, it tensions the spring 54 and shifts its stop 51 away. The boss 13 presses no longer against the shuttle that is then urged inwardly by the picker stick C. The roller 47 is no longer held by the shuttle and engages again the inside of the box B under the action of the spring 53 while the stop 50 rises and comes into register with the stop 51. The cam 18 that has continued its rotation has left the crank pin 52 of the lever 21 and the latter bears through its stop 51 against the stop 50 that prevents it from pressing against the boss 13.

When the provision of weft thread on the cop of the shuttle 41 is no longer sufficient, at the moment when the batten is in its operative position as shown at I in Fig. 5, the needle 35 of the sensing mechanism engages to a greater extent inside the shuttle and its stop 36 engages the notch 61 of the slider 37. The automatic shuttle changing movement is then obtained.

During the first half revolution of the crank-shaft of the loom the batten A moves from front to rear that is from the position I (Fig. 5) to the position II (Fig. 6).

During this movement, the needle of the sensing member is released with reference to the shuttle under the action of the cam 19 (Fig. 2) through the agency of the lever 20 driving also the slider 37 that is in its stop engaging position. The hooked lever 38 (Fig. 4) releases the arm 23 that drops in front of the cam 24 (Figs. 2 and 4). At the same time, the cam 18 has released the lever 21 that no longer bears against the boss 13 so as to allow the free starting of the shuttle 41 under the action of the picker stick disclosed hereinabove; the shuttle although it is exhausted retains still enough thread for executing a further reciprocation in the shed. The cam 24 has now moved into contact with the arm 23. This arm cannot move laterally so that the suitably shaped cam 24 providing for translational movement is shifted by the said arm in the direction of the arrow x together with the shaft 16 and its cams while compressing the spring 31. At the moment at which the translation controlling cam 24 engages the arm 23, the notch 25a of the disc 25 appears in front of the stationary stud 26 so that the disc 25 may enter a position on the other side of the stud 26.

The shaft 16 as it rotates brings then the solid portion of the disc 25 in front of said stud 26 so that the shaft 16 is held against outward shifting by the disc and the translation controlling

cam 24 is no longer operative. Through the action of the translational movement of the shaft 16, the cam 27 has come under the tail end of the lever 4, the cam 28 under the tail end of the lever 29 and the raising cam 22 under the translation controlling arm 23 while the cams 18 and 19 remain respectively in contact, the former with the lever 21 of the shuttle locking means, and the latter with the lever 20 of the sensing means. Through rotation of the shaft 16, the levers 4 submitted to the action of the cam 27 are lowered and their projections 4a are shifted downwardly inside the slopes 9 while they move off the plates 3 and the hooks thereon that are rigid with the batten A. They release thus said batten A from the frame 1 (position II of Fig. 6). At the same time the cam 28 raises the lever 29 that through the transmission 29a controls the movement of the cradle 39a of the magazine or holder 39 of full shuttles and produces the beginning downward movement of the next shuttle toward the box. At the end of the rearward movement of the batten A (position II, Fig. 6), the frame 1 is completely released with reference to the batten and the frame 1 under the action of the levers 4 controlled by the cam 27 and cooperating with the slopes 9 has moved slightly away from the frame 1 through a relative rocking of the two frames round the axis 8. The front wall 6 of the shuttle box has thus moved slightly away from the rear wall 1b and the full spare shuttle 48 has begun moving downwardly towards the box.

During the second half revolution of the crank-shaft of the loom, the batten A moves forwardly with its extension 3a—3—5 and leaves the frame 1 (Fig. 11 and position II of Fig. 7).

The levers 4 controlled by the cam 27 continue moving downwardly with their projections 4a moving along the slopes 9 of the front frame 1 and open the box B through the amount required for allowing an unrestricted introduction of the full shuttle 42 between the walls 1b and 6 of said box. The cam 28 continues controlling the downward movement of the shuttle 42 that drops on to the bottom of the box formed in frame 1. In the meantime the cam 22 has raised the translation controlling arm 23 that urges the lever 38 of the sensing mechanism into its original starting position (Fig. 4). During the third half-revolution of the crank-shaft, the batten A and its extension 3a—3b—3—5 return rearwardly. Under the action of the cam 27, the projections 4a of levers 4 begin rising over the cam slopes 9 of the front frame, the wall 6 of which closes over the frame 1 so that the shuttle 42 enters its operative position in contact with the boss 13. At the end of the rearward stroke of the batten A (position IV, Fig. 8), the projections 4a of the levers 4 rise and come into register with the hooks 5 of the extension 3a of the batten. During this half revolution the exhausted shuttle 41 has been urged forwardly by the picker stick towards the opposite side of the loom and the cradle 39a carrying the full shuttle 42 has been held against the bottom 1c of the box B.

During the fourth half revolution of the crank-shaft, the extension of the batten returns forwardly. The hooks 5 of the fittings forming an extension of the batten engage the crank pins 4a on the levers 4 and the batten carries along with it the frame 1 but with a lag such that the box B is no longer in alignment with the batten, the shoe 10 of the open box lying in its stead in said alignment.

At this moment the exhausted shuttle 41 enters said open box (Fig. 12 and position V, Fig. 9) and it arrives on to the surface of the shoe 10 that forms an independent partial closure for the receiving box. The shuttle is stopped against further progression by the stop 11 (Fig. 14) and is prevented from rocking by the cover 44 that is urged against it by its spring 12. During this forward movement of the batten, the shaft 16 finishes its complete revolution, the cam 28 provides for a downward movement of the lever 29 controlling the shuttle holder while the cradles 39a that formerly carried the full shuttle are released through the forward movement of the frame 1 and pass through the openings 1g in the rear wall 1. At the same time, the notch 25a of the locking disc 25 has arrived in front of the stud 26 and under the action of the spring 31, the shaft 16 is urged towards the right hand side of the loom in the direction of the arrow x. The cams 27 and 28 can now no longer reach the levers 4 and 29. At the end of the forward stroke of the batten, the frame 1 carried along by its inertia catches up the batten (Fig. 13 and position V, Fig. 10). The levers 4 under the action of a spring that is not illustrated rise completely and hold the frame 1 fast against the extension of the batten while the wall 6 of the outer box is held energetically between the frame 1 and the batten. During this last operation, the extension 3a of the batten engages partly under the shoe 10 and the open box 3b is positioned underneath the empty shuttle 41. At the same time, the extension of the batten causes the lever 14 to rock whereby the cover 44 also is released and allows the empty shuttle that is not completely held by the shoe 10 to rock and to pass through the box 3b and out of the same into a receiving basket.

The enlarged portion 75 to which the lever 14 is secured has for its object to provide an easier engagement of the empty shuttle inside the open box.

What I claim is:

1. An automatic shuttle changing apparatus for weaving looms adapted to operate during the time during which the shuttle box plays no useful part, comprising a batten, a shuttle box disconnectably carried by said batten, automatic means for returning the shuttle box rearwardly of the extreme rear position of the batten, a holder for substitute full shuttles registering with said rear position of the shuttle box rearwardly of the rear position of the batten, means for disconnecting the shuttle box from the batten, when the shuttle therein is substantially empty, means for holding the shuttle box in register with said holder for shuttle changing and means for reengaging the shuttle box with the batten when the latter has executed a complete reciprocating movement after disengagement.
2. An automatic shuttle changing apparatus for weaving looms comprising a batten, a rocking shaft for said batten, a frame pivotally secured to said shaft side by side with the batten in the longitudinal direction of the shaft, a shuttle box formed at the upper part of said frame and including a front wall pivotally secured to the frame body, a holder for substitute full shuttles registering with said rear position of the shuttle box rearwardly of the rear position of the batten, means for disconnecting the shuttle box from the batten, when the shuttle therein is substantially empty, means for holding the shuttle box in register with said holder for shuttle changing

and means for reengaging the shuttle box with the batten when the latter has executed a complete reciprocating movement after disengagement.

3. An automatic shuttle changing apparatus for weaving looms comprising a batten, a rocking shaft for said batten, a frame pivotally secured to said shaft side by side with the batten in the longitudinal direction of the shaft, a shuttle box formed at the upper part of said frame and including a front wall pivotally secured to the frame body, a holder for substitute full shuttles registering with said rear position of the shuttle box rearwardly of the rear position of the batten, a weft feeler carried by the pivoting frame, means whereby the operation of the weft feeler disconnects the shuttle box and frame from the batten, means for holding the shuttle box in register with said holder for shuttle changing and means for reengaging the shuttle box with the batten when the latter has executed a complete reciprocating movement after disengagement.

4. An automatic shuttle changing apparatus for weaving looms comprising a batten, a rocking shaft for said batten, a frame pivotally secured to said shaft side by side with the batten in the longitudinal direction of the shaft, a shuttle box formed at the upper part of said frame and including a front wall pivotally secured to the frame body, a holder for substitute full shuttles registering with said rear position of the shuttle box rearwardly of the rear position of the batten, a lever system adapted to move between a position for which it secures the frame to the batten and simultaneously holds the front wall of the shuttle box in its closing position and a release position for which the shuttle box frame is released with reference to the batten and the shuttle box front wall is open, a cam and slideways on the front wall of the shuttle box cooperating with the lever system for controlling the position of said system, means for rendering said cam operative when the shuttle in the box is substantially empty and means for automatically changing the shuttle in the shuttle box when the frame is disconnected from the batten.

5. An automatic shuttle changing apparatus for weaving looms comprising a batten, a rocking shaft for said batten, a frame pivotally secured to said shaft side by side with the batten in the longitudinal direction of the shaft, a shuttle box formed at the upper part of said frame and including a front wall pivotally secured to the frame body, a holder for substitute full shuttles registering with said rear position of the shuttle box rearwardly of the rear position of the batten, a lever system adapted to move between a position for which it secures the frame to the batten and simultaneously holds the front wall of the shuttle box in its closing position and a release position for which the shuttle box frame is released with reference to the batten and the shuttle box front wall is open, a cam and slideways on the front wall of the shuttle box cooperating with the lever system for controlling the position of said system, a weft feeler carried by the frame, a shaft rotatably carried by the frame carrying the abovementioned cam, means for causing said shaft to rotate at a speed corresponding to one revolution for two reciprocations of the batten, complementary cams keyed to said shaft controlling respectively the operation of the weft feeler, and the feeding of a substitute shuttle from the shuttle holder to the shuttle

box, a cam on the camshaft adapted to provide for a longitudinal shifting of the camshaft under the action of the weft feeler, the cams controlling the levers connecting the frame with the batten and the operation of the holder being operative only when the shaft is in its longitudinally shifted position.

6. An automatic shuttle changing apparatus for weaving looms comprising a batten, a rocking shaft for said batten, a frame pivotally secured to said shaft side by side with the batten in the longitudinal direction of the shaft, a shuttle box formed at the upper part of said frame and including a front wall pivotally secured to the frame body, a holder for substitute full shuttles registering with said rear position of the shuttle box rearwardly of the rear position of the batten, a lever system adapted to move between a position for which it secures the frame to the batten and simultaneously holds the front wall of the shuttle box in its closing position and a release position for which the shuttle box frame is released with reference to the batten and the shuttle box front wall is open, a cam and slideways on the front wall of the shuttle box cooperating with the lever system for controlling the position of said system, a weft feeler carried by the frame, a shaft rotatably carried by the frame carrying the abovementioned cam, means for causing said shaft to rotate at a speed corresponding to one revolution for two reciprocations of the batten, complementary cams keyed to said shaft controlling respectively the operation of the weft feeler, and the feeding of a substitute shuttle from the shuttle holder to the shuttle box, a cam on the camshaft including a lateral boss, a linkage controlled by the weft feeler and adapted to engage the path of said boss when the feeler has sufficiently engaged a shuttle in the shuttle box for constraining the boss and therewith the corresponding cam and cam shaft to be shifted longitudinally, the cams controlling the levers connecting the frame with the batten and the operation of the holder being operative only when the shaft is in its longitudinally shifted position.

7. An automatic shuttle changing apparatus for weaving looms comprising a batten, a rocking shaft for said batten, a frame pivotally secured to said shaft side by side with the batten in the longitudinal direction of the shaft, a shuttle box formed at the upper part of said frame and including a front wall pivotally secured to the frame body, a holder for substitute full shuttles registering with said rear position of the shuttle box rearwardly of the rear position of the batten, a lever system adapted to move between a position for which it secures the frame to the batten and simultaneously holds the front wall of the shuttle box in its closing position and a release position for which the shuttle box frame is released with reference to the batten and the shuttle box front wall is open, a cam and slideways on the front wall of the shuttle box cooperating with the lever system for controlling the position of said system, a weft feeler carried by the frame, a shaft rotatably carried by the frame carrying the abovementioned cam, means for causing said shaft to rotate at a speed corresponding to one revolution for two reciprocations of the batten, complementary cams keyed to said shaft controlling respectively the operation of the weft feeler, and the feeding of a substitute shuttle from the shuttle holder to the shuttle box, a cam on the camshaft including a lateral boss, a linkage controlled by the weft feeler and adapted

to engage the path of said boss when the feeler has sufficiently engaged a shuttle in the shuttle box for constraining the boss and therewith the corresponding cam and camshaft to be shifted longitudinally, the cams controlling the levers connecting the frame with the batten and the operation of the holder being operative only when the shaft is in its longitudinally shifted position, a mechanism carried by the frame for locking the shuttle inside the shuttle box, and a cam on the camshaft controlling said mechanism.

8. An automatic shuttle changing apparatus for weaving looms comprising a batten, a rocking shaft for said batten, a frame pivotally secured to said shaft side by side with the batten in the longitudinal direction of the shaft, a shuttle box formed at the upper part of said frame and including a front wall pivotally secured to the frame body, a holder for substitute full shuttles registering with said rear position of the shuttle box rearwardly of the rear position of the batten, a lever system adapted to move between a position for which it secures the frame to the batten and simultaneously holds the front wall of the shuttle box in its closing position and a release position for which the shuttle box frame is released with reference to the batten and the shuttle box front wall is open, a cam and slideway on the front wall of the shuttle box cooperating with the lever system for controlling the position of said system, a weft feeler carried by the frame, a shaft rotatably carried by the frame carrying the above-mentioned cam, means for causing said shaft to rotate at a speed corresponding to one revolution

for two reciprocations of the batten, complementary cams keyed to said shaft controlling respectively the operation of the weft feeler, and the feeding of a substitute shuttle from the shuttle holder to the shuttle box, a cam on the camshaft including a lateral boss, a linkage controlled by the weft feeler and adapted to engage the path of said boss when the feeler has sufficiently engaged a shuttle in the shuttle box for constraining the boss and therewith the corresponding cam and camshaft to be shifted longitudinally, the cams controlling the levers connecting the frame with the batten, and the operation of the holder being operative only when the shaft is in its longitudinally shifted position, a mechanism carried by the frame for locking the shuttle inside the shuttle box, and a cam on the camshaft controlling said mechanism and a cam on the camshaft for returning said feeler linkage into its normal inoperative position.

EMILE ACHILLE BUTIN.
